UNITED STATES PATENT OFFICE

GEORGE L. BROWNELL, OF WORCESTER, MASSACHUSETTS

DEVICE FOR REMOVING MOISTURE FROM FLEXIBLE STRIP MATERIAL

Application filed November 14, 1929. Serial No. 407,266.

The present invention relates to a device for removing moisture from the surface of flexible strip material, the device of the present invention being particularly adapted for removing excess moisture from both sides of a moving strip of flexible material that has just passed through a bath of liquid which adheres to the strip.

While the device of the present invention is not limited for use in connection with any particular machine or method of manufacture, it has particular utility in connection with the treatment of a moving strip of paper, or cloth, with a suitable liquid adhesive or size prior to the strip being twisted into a filament. When so twisting a strip having adhesive applied thereto, it is essential that excess moisture in the form of adhesive be removed from the strip, on both sides, so that only enough adhesive remains to insure the necessary binding of the strip as it is twisted. The above and other advantageous features of my invention will hereinafter more fully appear with reference to the accompanying drawings, in which:—

Fig. 1 is a view partially in section, and partially in side elevation, of a moisture removing device embodying the invention, the parts being shown in an inoperative position.

Fig. 2 is a view similar to Fig. 1 illustrating the parts in position to operate on the moving strip of material.

Fig. 3 is a plan view of the parts shown in Fig. 1.

Fig. 4 is a fragmentary sectional view showing certain details of the device.

Like reference characters refer to like parts in the different figures.

Referring first to Fig. 1, the moisture removing device is shown in connection with a receptacle 1 for containing a suitable liquid adhesive 2 such as glue, mucilage, or a suitable liquid size with which it is desired to coat a strip 3 of flexible material such as paper or cloth. The strip 3 is led to the device from a suitable supply, not shown, the strip passing partially around a guide rod 4 in the direction of the arrow and leaving the device in a generally downward direction after passing through the adhesive receptacle 1 and be-

ing acted upon by the moisture removing device.

The moisture removing device is supported by a frame member 5 extending along the receptacle 1, the frame member 5 carrying a bracket 6 adjustably secured thereto by means of bolts 7 received in slots 8 provided in the bracket 6. As best shown in Fig. 3, the bracket 6 provides spaced arms 9 and 10 of different length between which is mounted a shaft 11 carrying a roll 12. The shaft 11 also serves to pivotally support a bell-crank lever, one arm 13a of which carries a rod 14 at its free end. The other arm 13b of the bell-crank lever carries a pin 15 near its free end, the purpose of which is to maintain the rod 14 in an inoperative, or operative, position with respect to the strip 3 and the receptacle 1 containing the adhesive 2.

As best shown in Fig. 1, when the device is in inoperative condition, the lever arm 13b is held in a nearly vertical position in which the rod 14 at the end of the other arm 13a is raised above the receptacle 1 with its lower surface just in engagement with the upper surface of the strip 3 as it passes from the guide rod 4. The lever arm 13b is maintained in this position by the reception of the pin 15 in a notch 16 provided by a latch lever 17 pivotally mounted on the long arm 9 of the bracket 6 by the stud 17a. In this position, the unbalanced weight of the rod 14 at the end of the lever arm 13a tends to maintain the pin 15 in the notch 16 and so prevent the rod 14 from pressing on the strip 3.

When it is desired to place the device in operation, so as to remove excess moisture from the strip 3 after it has passed through the adhesive 2 in the receptacle 1, the latch lever 17 is turned to release the pin 15 from the notch 16, whereupon the lever arm 13a is free to swing downwardly about the shaft 11 and carry the strip 3 into the adhesive 2 carried by the receptacle 1. The position then occupied by the lever arm 13a and rod 14 is shown in Fig. 2, from which it is evident that the strip 3 is carried down around the stationary roll 12 into the lower portion of the receptacle 1 so that a considerable

length of the strip 3 is immersed in the adhesive 2. The rod 14 is adapted to be locked in this position by means of the pin 15 on the lever arm 13b being received in a second notch 18 provided in the latch lever 17. Obviously the notch 18 limits the downward movement of the rod 14 and so prevents the strip 3 touching the bottom of the receptacle 1 and at the same time the pressure exerted by the latch lever 17 prevents the pull on the strip 3 from moving the rod 14 upwardly in the receptacle 1.

When the downward movement of the rod 14 carries the strip 3 into the lower portion 15 of the adhesive receptacle 1, it also moves the strip into engagement with the free edge of a scraping blade 19 carried by a cylindrical guide rod 20 extending parallel to and at substantially the same height as the roll 12. The rod 20 is cut away at one side to present a flat surface to which the blade 19 is clamped by means of set screws 21. In order to insure the setting of the rod 20 with its blade 19 at the desired angle, the reduced 25 end portion 20a of the rod 20 is received in seats 22 provided on opposite sides of a slot 23 extending into the end of the long arm 9 of the bracket 6, see Fig. 1. The split portions of the arm 9 beyond the seats 22 are 30 adapted to be drawn together by means of a set screw 24 to cause the seats 22 to tightly engage the reduced portion 20a of the rod 20 and thereby securely lock the guide rod 20 against turning after the blade 19 has been 35 set at the desired angle.

It is apparent from Fig. 2 that with the rod 14 holding the strip 3 down in the receptacle 1, the strip will be held in contact with the free edge of the blade 19, from which it passes around the periphery of the rod 20 before leading downwardly to the machine for twisting or otherwise operating on the moistened strip. Therefore, as the strip 3 is drawn from the receptacle 1, the under surface thereof in engagement with the blade 19 will have all excess moisture removed therefrom, such excess moisture falling back into the receptacle. Furthermore, the moist adhesive remaining on the lower surface of the strip 3, after engagement with the blade 19, will be so evenly distributed that passage of the strip over the surface of the guide rod 20 will not tend to dry the strip when once the rod itself becomes moistened.

At the same time that the blade 19 is operating to remove excess moisture from the under surface of the strip 3, a second blade 25 is operating to remove excess moisture from the upper surface of the strip 3 as it emerges 60 from the receptacle 1. This blade 25 is carried by a rod 26 extending parallel to the rod 20, one side of the rod 26 being cut away to provide a flat surface 26a against which the blade 25 is clamped by means of set screws 27. As best shown in Fig. 3, the rod

26 provides a reduced portion 28 tightly received in a bushing 29 turnable within an opening 30 provided near the end of the bracket arm 9. While the bushing 29 is held against longitudinal movement within the opening 30 by means of a collar 31 held by a set screw 32, turning of the bushing 29 permits the blade 25 carried by the rod 26 to be moved into either an operative or inoperative position with respect to the strip 3.

As best shown in Fig. 4, the surface of the bushing 29 provides a notch 33 that is adapted to receive a ball 34 carried in an opening 35 formed in a boss 36 projecting from the arm 9. The ball 34 is forced into engagement with the notch 33 by means of a spring 37 retained by a plug 38, and the ball 34 is adapted to hold the bushing 29 in such a position that the blade 25 is maintained out of engagement with the strip 3, as indicated in full lines in Fig. 4. The bushing 29 also provides another notch 39 that is adapted to receive the ball 34 when the blade 25 is turned downwardly from its inoperative position of Fig. 1 to the position shown in Fig. 2 in which the free edge of the blade 25 engages the upper surface of the adhesive moistened strip 3. In turning the blade 25 from the position of Fig. 1 into the position of Fig. 2, enough force must be exerted to cause the ball 34 to be unseated from the notch 33 and obviously when the blade 25 has been turned to engage a strip 3 the ball 34 will be seated into the other notch 39 thereby holding the blade 25 in its scraping position.

Therefore, when both blades 19 and 25 are in engagement with opposed surfaces of the strip 3, as shown in Fig. 2, all the excess moisture will be removed from the strip as it is drawn between the blades and this action will continue so long as the rod 14 presses the strip downwardly into the receptacle 1. When it is desired to discontinue operation of the device, the blade 25 is first turned upwardly into the position shown in Fig. 1, this operation being readily accomplished by seizing the collar 31 and turning it until the ball 34 is seated in the notch 33. This position will be indicated by a sudden increase in the resistance to turning the collar 31, and obviously the blade 25 will be maintained in this inoperative position by pressure of the ball 34. The latch lever 17 is then turned upwardly far enough to release the pin 15 from the notch 18, whereupon the lever arm 13b can be freely turned to lift the roll 14 out of the receptacle 1. The rod 14 can then be locked in its inoperative position by seating the pin 15 in the outer notch 16 as indicated in Fig. 1. With the blade 25 and the rod 14 in these positions, a new strip 3 can be fed down under the guide rod 4 and over the rod 20 without engaging either of the scraping blades 19 or 25 and without coming in contact with the adhesive in the receptacle 1.

Then when the new strip has been properly received in the machine for twisting or otherwise handling it, the strip can be quickly immersed in the adhesive 2 by unlocking the lever arm 13b and causing the rod 14 to carry a strip into the receptacle. The blade 25 can then be quickly moved into scraping position by turning the collar 31, this position being indicated by an increased resistance to turn-

10 ing when the ball 34 is seated in the notch 39.

From the foregoing it is apparent that by the present invention there is provided an extremely simple and effective device for removing excess moisture from opposite surfaces of a strip of flexible material that has been previously drawn through a receptacle containing a suitable adhesive. The operation of the opposed scraping blades 19 and 25 effectively prevents any excess moisture in the form of adhesive being carried past the blades into the twister or other machine for operating on the strip, all excess moisture thus removed automatically draining back into the receptacle 1.

25 I claim,

1. In a device of the class described, the combination with a fluid receptacle, a fixed scraper blade mounted above the receptacle, a rotatably mounted scraper blade and a roll 20 mounted on a fixed axis above said receptacle and opposite to said blades, of a rod pivotally mounted on the same axis as said roll, said rod being turnable to immerse a strip of flexible material in said receptacle, means 35 for locking said rod to maintain said strip at a predetermined depth in said receptacle intermediate the points of engagement of its under surface with said roll and with the edge of said stationary blade, and means for 40 maintaining said rotatably mounted blade in position to engage the upper surface of said strip adjacent to said fixed blade.

2. In a device of the class described, the combination with a fluid receptacle, a fixed 45 scraper blade mounted above the receptacle, a rotatably mounted scraper blade and a roll mounted on a fixed axis above said receptacle and opposite to said blades, of a rod pivotally mounted on the same axis as said roll, 50 means for locking said rod in one position to maintain a flexible strip immersed a predetermined amount in said receptacle with its opposed surfaces in engagement with the edges of said blades, and means for maintaining 55 said rod in another position in which said strip may pass directly over said receptacle out of engagement with both of said blades, said rotatable blade being swung out of engagement with said strip in the second 60 named position of said rod.

GEORGE L. BROWNELL.
